CLAIM

I claim the ornamental design for a skateboard deck, as shown and described.

DESCRIPTION

Portions of the disclosure of this patent document contain material that is subject to copyright protection. The copyright owner has no objection to the facsimile reproduction by anyone of the patent document or the patent disclosure as it appears in the Patent and Trademark Office file or records, but otherwise reserves all copyright rights whatsoever.

FIG. 1 is a top view of a skateboard deck with a surface ornamentation consisting of a mirror-like reflective appearance according to the new design.

FIG. 2 is a right side view of the skateboard deck with a surface ornamentation consisting of a mirror-like reflective appearance.

FIG. 3 is a left side view of the skateboard deck with a surface ornamentation consisting of a mirror-like reflective appearance.

FIG. 4 is a bottom view of the skateboard deck with a surface ornamentation consisting of a mirror-like reflective appearance.

FIG. 5 is a rear view of the skateboard deck with a surface ornamentation consisting of a mirror-like reflective appearance.

FIG. 6 is a front perspective view of the skateboard deck with a surface ornamentation consisting of a mirror-like reflective appearance; and,

FIG. 7 is a bottom perspective view of the skateboard deck with a surface ornamentation consisting of a mirror-like reflective appearance.
